APPARATUS FOR TAPING PACKAGES

George O. Cook, Camp Hill, Pa.

Application July 29, 1954, Serial No. 446,686

2 Claims. (Cl. 53—198)

(Granted under Title 35, U.S. Code (1952), sec. 266)

The invention described herein, if patented, may be manufactured and used by or for the Government for governmental purposes, without the payment to me of any royalty thereon.

The present invention relates broadly to packaging and more particularly to a method of and apparatus for applying adhesive tape to packages for reinforcing the same.

Large quantities of canned goods and like articles are packed for storage and shipment in conventional corrugated fiberboard cartons or boxes. These cartons are rectangular in shape and are provided at one side with overlapping closure flaps, which are held closed by suitable cement or the like. When the closed cartons are held in storage warehouses for a considerable length of time, the cement tends to dry out and weaken, and in subsequent handling of the cartons the closure flaps tend to burst open, which of course results in the spilling of the contents of the cartons.

To prevent this, the practice has arisen of applying a band or bands of adhesive tape around the cartons and across the outermost pair of closure flaps for reinforcing the horizontal seams or fold lines of the carton and also for preventing the closure flaps from opening in the event that the cement holding them closed dries out and fails. At the present time, the reinforcing adhesive tape is being applied to cartons of the above-mentioned type by hand, and this is time consuming and requires considerable labor. Machines have been developed to apply the reinforcing adhesive tape to the cartons, but such machines are very complicated in construction and mode of operation, and have proven impractical and very expensive to build and maintain.

Accordingly, it is a primary object of the present invention to provide a method and apparatus for applying the reinforcing tape to cartons of the above-mentioned type in an expeditious manner and with a minimum of labor and expense, thus eliminating the above-mentioned disadvantages inherent in the presently employed practices for applying reinforcing tape to fiberboard cartons and the like.

Another object of the invention is to provide apparatus for applying reinforcing tape to packages which is highly simplified in construction, reliable and efficient in operation and relatively inexpensive to manufacture.

A further important object is to provide a method and apparatus of the above-mentioned character which greatly reduces the manual labor involved for applying the reinforcing tape to the packages.

Still another object is to provide apparatus of the above-mentioned character which is adjustable to vary the tension on the adhesive tape so that the tape may engage the package with a proper degree of pressure to assure adhesion between the tape and the package.

Other objects and advantages of the invention will be apparent during the course of the following description.

In the accompanying drawings, forming a part of this application, and in which like numerals are employed to designate like parts throughout the same,

2

Figure 1 is a perspective view of apparatus employed in the practice of the adhesive tape applying method,

Figure 2 is a side elevation of the same,

Figure 3 is a plan view of the apparatus,

Figure 4 is a transverse vertical section taken on line

4—4 of Figure 3, and

Figure 5 is an enlarged fragmentary vertical section taken on line 5—5 of Figure 2.

In the drawings, where for the purpose of illustration is shown a preferred embodiment of the invention, the numeral 10 designates generally a section of roller conveyor of any preferred length, and being of conventional construction. The roller conveyor section 10 comprises the usual side rails or bars 11, which support a multiplicity of parallel spaced rollers 12, extending therebetween at right angles thereto and having their opposite ends journaled upon the side rails 11 for rotation. The roller conveyor section 10 is supported at its ends by legs 13, suitably rigidly secured thereto, and these legs support the roller conveyor section at the desired elevation and in a horizontal position.

As shown in the drawings, a number of the conveyor rollers 12 near the longitudinal center of the roller conveyor section 10 are omitted. This provides an empty space between the innermost pair of rollers 12 and between the side rails 11, Figure 3. At the longitudinal center of the section 10 of the roller conveyor, a horizontal transverse support plate or bar 14 extends transversely between the side rails 11, at right angles thereto, and has its ends rigidly secured to the bottoms of the side rails by welding or the like. The support plate 14 has a suitable thrust type ball bearing assembly 15 rigidly mounted thereon at its longitudinal center and at the transverse center of the roller conveyor section 10, as shown. The ball bearing assembly 15 includes an upper rotatable member or race 16, which revolves about the vertical axis of the ball bearing assembly, and the race 16 is disposed substantially flush with the top of the roller conveyor section 10, as shown.

40 A horizontal turntable or plate 17, which is preferably square, is suitably rigidly secured to the upper race 16 of the ball bearing assembly for rotation therewith in a horizontal plane, and the ball bearing assembly 15 is at the center of the turntable 17. The bottom of the turntable 17 is disposed close to and slightly above the tops of the rollers 12, so as to clear the same during rotation. The top of the turntable 17 preferably projects a slight distance above the tops of the rollers 12, such as one inch, for a purpose to be described. The turntable 17 is freely rotatable about the vertical axis of the ball bearing assembly 15.

55 A portable vertical shaft or standard 18 of a desired height is provided, and this standard has a heavy-weighted base or pedestal 19 rigidly secured to its lower end to provide stability for the standard. The top of the standard 18 extends for a substantial distance above the top of the turntable 17, as shown.

60 A vertically adjustable collar or sleeve 20 is mounted upon the standard 18 above the elevation of the turntable 17, and suitable adjustable clamping means 21 are provided upon the collar 20 so that the same may be adjusted vertically or longitudinally of the standard 18 and locked in the selected adjusted position. A roll 22 of pressure sensitive adhesive tape is journaled for rotation upon the standard 18 above the adjustable collar 20, and the core or hub 23 of the adhesive tape roll slidably engages the top of the collar 20 as shown in Figure 5. The adhesive tape employed is preferably a filament reinforced cellulosic type of gummed tape, although any preferred type of pressure sensitive adhesive tape may be used, as found desirable. Above the

tape roll 22, a vertically adjustable brake collar or sleeve 24 is mounted upon the standard 18 and secured thereto by means of a setscrew or the like. The brake collar 24 has its lower end frictionally engaging the core 23 of the tape roll, as shown. The collar 24 may be adjusted upon the standard 18 and locked in the selected adjusted position to provide the desired frictional braking action upon the rotatable tape roll 22, for a purpose to be described. Also, by adjusting both of the collars 20 and 24 and the tape roll 22 longitudinally of the standard 18, the elevation of the tape roll above the turntable 17 may be varied as found desirable.

The use of the above described apparatus in the practice of the method is as follows:

The standard 18 is set up near one side of the roller conveyor 10, and preferably adjacent to a corner of the turntable 17, as shown. It is preferred to arrange the standard as close to the turntable 17 as possible, allowing sufficient clearance for the corners of the turntable to pass the standard 18 during rotation of the turntable. The operator of the apparatus may stand at the same side of the roller conveyor 10 upon which the standard 18 is located and near the adjacent side of the turntable. The adjustable collars 20 and 24 and the tape roll 22 are arranged at the desired elevation upon the standard 18, for applying the adhesive tape to boxes or cartons of a particular size and height. The braking collar 24 is adjusted to provide a desired tension upon the adhesive tape to be unwound from the tape roll 22.

The boxes or cartons 26 containing goods or the like are now placed upon the roller conveyor section 10 near the end of the conveyor remote from the standard 18. This may be done by an additional operator, if desired. The cartons 26 are initially arranged upon their sides, Figure 1, with the meeting line 27 between their closure flaps 28 arranged horizontally, and preferably facing the side of the conveyor adjacent to which the standard 18 and the operator are located. Each box or carton 26 is now advanced longitudinally of the conveyor 10 toward the square turntable 17, which as previously stated, projects above the tops of the rollers 12. The forward side of each carton 26 will engage the rear edge of the turntable 17, which is initially arranged transversely of the turntable 10 or parallel to the rollers 12. Upon engaging the rear edge of the turntable 17, the operator adjacent to the standard 18 merely pivots or swings each carton 26 about the fulcrum provided by the elevated rear edge of the turntable 17 and turns the carton 26 over upon the turntable so that the meeting line 27 between the flaps 28 will then be disposed vertically at the side of the turntable nearest the standard 18, Figure 1. With this arrangement, it is unnecessary for the operator to lift each carton 26 when placing it upon the turntable, and this is an advantage, since the cartons bearing canned goods and the like may be quite heavy.

Each carton 26 is thus preferably arranged centrally upon the turntable 17 as shown in Figure 1. The tape roll 22 will now be disposed substantially at the vertical center of the carton 26 as it rests upon the turntable 17, and the tape roll is disposed near one forward corner of the carton as best shown in Figure 3. The operator now applies the free end of the adhesive tape from the roll 22 to the forward side of the carton 26, preferably near the forward corner of the carton adjacent to the standard 18. When this has been done, the operator grasps the carton 26 upon the turntable and spins or rotates it in the direction of the arrow, Figure 3, for one or more complete revolutions, and the carton 26 and turntable 17 will turn as a unit upon the ball bearing assembly. As this occurs, the adhesive tape will be unwound from the roll 22 and applied about the carton 26 in a horizontal band or loop which will extend trans-

versely across the vertical meeting line 27 and closure flaps 28. The adhesive tape band 29 thus applied to the carton 26 will adhere firmly to the four vertical sides of the carton due to the fact that sufficient tension upon the adhesive tape as it is unwound from the roll 22 is applied by the braking collar 24. The tape engages the sides of the rotating carton 26 under tension, and this causes the tape to contact the carton with sufficient pressure to assure its adhesion thereto.

When one or more revolutions of the carton 26 and turntable have been completed, the operator merely severs the adhesive tape between the roll 22 and the forward corner of the carton 26 which is now nearest the standard 18 with a razor blade 30 or the like, as shown at 31 in Figure 4. The operator may press the free trailing end of the adhesive tape formed by the severing operation against the side of the carton by hand, if desired, so that no portion of the adhesive tape band or loop 29 will be free from adhesion to the carton. This last step may be omitted if preferred.

If it is desired to apply additional horizontal bands or loops 29 of adhesive tape to the carton 26, after a number of the cartons have had one reinforcing band of tape applied thereto near their vertical centers, the tape roll 22 and collars 20 and 24 may be adjusted vertically upwardly or downwardly upon the standard 18, and the cartons 26 may be again advanced along the roller conveyor 10 to the turntable 17, and the above described operation repeated. By doing this, additional horizontal bands 29 of tape may be applied to the cartons above or below the center band 29, and the cartons will be further reinforced across the flaps 28 and about all four corners of the cartons parallel to the meeting line 27.

After the reinforcing bands of adhesive tape have been thus applied to the cartons 26, the operator near the standard 18 merely pushes each carton forwardly off of the turntable 17, and the cartons are advanced toward the forward or discharge end of the roller conveyor 10, where another operator may receive them for transportation to any desired point.

It is thus seen that the above described method and apparatus are employed effectively and with a minimum of manual labor for applying one or more bands of reinforcing adhesive tape about the cartons or packages 26 in a manner to reinforce the closure flaps 27 against opening in the event that the cement holding them closed should fail. The tape also reinforces the four corners of the cartons which are most likely to burst open during handling, storage and the like.

It is usually not necessary to apply tape to the cartons at right angles to the reinforcing bands 29 of tape described above, but in the event that it should be desired to do this, it is merely necessary to advance the cartons along the roller conveyor in the same manner as above described, but with the closure flaps 28 arranged at the tops or bottoms of the cartons as they are placed upon the turntable 17. When this is done, and the above described operation is carried out, bands of adhesive tape may be applied to the cartons at right angles to the bands 29, and the cartons will be effectively reinforced upon all sides of the same.

It should be mentioned that the standard 18 is portable and need not be bolted to the floor. It is entirely a matter of choice on the part of the operator as to which side of the conveyor 10 the standard 18 is to be located. Different operators may desire to position the standard at a slightly different initial position than that illustrated in the drawings, and the precise location of the standard may be adjusted somewhat as found most convenient by the operator. If the standard 18 is located at the opposite side of the conveyor from that illustrated in the drawings, the cartons or boxes are merely advanced

upon the conveyor in the opposite direction, and the operation of the apparatus will be otherwise identical.

It is to be understood that the form of the invention, herewith shown and described is to be taken as a preferred example of the same, and that various changes in the shape, size and arrangement of parts of the apparatus, as well as various slight changes in the method steps may be resorted to, without departing from the spirit of the invention or scope of the subjoined claims.

I claim:

1. Apparatus for use in applying vertically-spaced reinforcing tapes to a non-circular package, comprising a substantially horizontal roller conveyor table, a substantially horizontal rectangular turntable journaled upon the roller conveyor table and spaced somewhat above the tops of the rollers of the conveyor table to provide a fulcrum for manually pivoting said package about the near edge of said turntable onto the center of said turntable into proper position for taping as said package is advanced along the conveyor table, an upright standard positioned near one side of the turntable and extending above the turntable, a collar mounted on said standard, said collar being vertically movable on said standard for a distance approximately equal to the height of said package, and said standard being free from obstructions to the vertical adjustment of said collar on said standard for a distance at least as great as the height of the package, and a roll of pressure-sensitive adhesive tape journaled upon the standard above said collar and slidably contacting said collar; whereby upon vertical movement of said collar to a predetermined height above said turntable, and application of the free end of said adhesive tape to said package, said adhesive tape is un-

wound from said roll and applied about said package in a substantially horizontal band when said turntable and package are conjointly rotated, and whereby upon a second vertical positioning of said last-mentioned collar to a height different from said first height and re-application of the free end of said adhesive tape to said package, said adhesive tape is again unwound from said roll and applied about said package in a second substantially horizontal band vertically spaced from said first band when said turntable and package are again conjointly rotated.

2. Apparatus according to claim 1, wherein a vertically movable brake collar is mounted upon said upright standard above said roll of adhesive tape for frictionally engaging said roll to regulate the tension on said adhesive tape as it is unwound from said roll and applied about said package.
